FRACTURE NAIL AND BONE PLATE

Edward J. Haboush, Brooklyn, N. Y.

Application October 28, 1947, Serial No. 782,503

3 Claims. (Cl. 128—92)

1

This invention relates to devices for use in the fixation of fractures, and it relates particularly to a novel fracture nail and bone plate.

Due to the difficulties encountered in the setting and fixation of fractures of the neck of the femur, a great many different types of fracture nails or pins have been developed heretofore. Also, because of the difficulties sometimes encountered in the treatment of fractures of other bones, it has been necessary to provide various types of plates which can be affixed to the fragments of the bone by means of screws to retain the fragments in their proper position to allow them to knit together properly.

All of the prior nails and bone plates have, as a function, the retention of the fractured bone fragments against shifting relatively when subjected to torque, tension or impact, or combinations thereof.

When the neck of the femur is fractured, it has been found desirable to connect the fragments on opposite sides of the fractures by means of pins or screws or nails driven through the fragments to prevent relative shifting or rotation of the fragments under torque forces or the thrust exerted by the muscles of the patient. These prior nails or pins are very satisfactory for this purpose. However, their use is limited to this one type of operation. They cannot be used for fixation of fractures of the shaft of the femur or fractures, for example, of the shafts of other bones, for the reason that they do not lie flat against the bone or are provided with projecting flanges or reinforcing ridges which irritate the flesh overlying them. Therefore, for the fixation of these latter types of bone fractures, it has been necessary to provide bone plates which are substantially different in shape and size from the pins and nails referred to above.

Inasmuch as each of the pins, nails and bone plates has been developed for a specialized purpose, it is necessary to provide a great variety of shapes and sizes to meet all conditions. In modern hospitals, thirty to forty different kinds of bone pins, nails, plates, etc., may be kept in stock to meet all requirements.

An object of the present invention is to provide a device for the fixation of fractures which is of such construction that it may be used with equal facility as a bone nail or a bone plate or as a combined nail and plate.

Another object of the invention is to provide a device for the fixation of fractures of almost any kind so that a relatively small variety of

these devices can be used for the fixation of substantially all types of fractures.

Other objects of the invention and advantages thereof will become apparent from the following description of typical forms of devices embodying the present invention.

In accordance with the present invention, a fracture fixation device is provided which is characterized by high resistance to twisting under torque, is highly resistant to bending and is of such shape that it can be used as a bone plate or a bone nail or a combination of the two.

More particularly, devices of the type embodying the present invention may consist of a strip of corrosion-resistant metal, such as, for example, stainless steel or other metal commonly used for this purpose which is provided with flanges at its opposite edges that extend outwardly in both directions from the strip to impart rigidity to the member. These flanges are of special advantage in anchoring the device when it is driven into the bone, inasmuch as they provide edge portions extending in opposite directions which tend to prevent relative rotation of the bone fragments with respect to each other and with respect to the fixation device. These flanges are, however, of relatively shallow height so that if the device is used as a bone plate, the flanges do not project sufficiently to irritate the tissues overlying the device after it has been applied to the fractured bone.

To facilitate the application of the device to the bone, either as a nail, or as a bone plate, the center portion of the device is provided with a series of apertures of a known length so that by X-ray examination during the use of the device as a bone nail, for example, the depth to which the nail has been driven can be determined by referring to the number of openings visible during the X-ray examination. The apertures have the further function of permitting the device to be secured by means of screws to the shaft of a bone in the usual way.

Devices of the type described generally above can be made in a standard length; if desired, and portions thereof may be cut off for use as nails or as bone plates as may be required. Also, while the device has sufficient rigidity to prevent relative rotation between the fragments produced by fracture of the neck of the femur, it can be bent by means of a suitable small metal brace to form an additional bone plate extension or to conform it to the shape of a bone to which it is to be applied.

For a better understanding of the present in-

vention, reference may be had to the accompanying drawings, in which:

Figure 1 is a plan view of a typical form of device embodying the present invention;

Figure 2 is a view in section taken on line 2—2 of Figure 1;

Figure 3 is a perspective view of a modified form of device embodying the present invention illustrating a feature of the device which is useful in guiding it into position for the fixation of a fracture;

Figure 4 is a view in section taken on line 4—4 of Figure 3;

Figure 5 is a view illustrating the use of the device for fixation of a fracture of the neck of the femur; and

Figure 6 is a view in section taken on line 6—6 of Figure 5.

The forms of the invention described herein-after are typical embodiments thereof which can be varied in size and proportions as the purpose demands.

Referring now to Figures 1 and 2 of the drawings, a typical device embodying the present invention may consist of a strip 10 of corrosion-resistant metal, such as, stainless steel, which has a narrow center web portion 11 and right-angularly related flanges 12 and 13 at its opposite edges. The flanges 12 and 13 project on opposite sides of the center web, as best shown in Figure 2, so that oppositely directed narrow edge portions are provided which reinforce the device and provide edges for anchoring the device in the bone as described hereinafter. The device 10 will be referred to hereinafter as a nail, but as will become apparent, it is useful as a bone plate, a bone pin or nail, or a combination thereof. Therefore, the term "nail" as it is applied to the invention should be construed as covering a device useful as a bone pin, a bone nail and/or a bone plate.

The length of the nail 10 may be modified and preferably is of substantially greater length than would be required for any usual type of fracture fixation operation. In this way, the nail 10 may be used in its full length for the fixation of a fracture if needed or it can be cut with an ordinary metal cutting device to a desired shorter length. In order to indicate quickly the length of the section to be severed from the nail 10, it may be provided with a plurality of apertures 14 of a predetermined length, for example, one half inch, these apertures being spaced apart lengthwise of the strip by webs 15, each of which is the same length, for example, a quarter of an inch. Thus, the apertures and the webs therebetween provide an accurate indication of the length of any section or segment of the nail 10 which may be required. Also, the apertures and the interposed webs 15 are useful in determining the depth of insertion of the nail into the bone by examination with X-rays.

Referring now to Figures 5 and 6, the nail 10 may be used in the conventional way as a bone nail to fix the fragments B1 and B2 of the femur F by driving it through the two fragments. Inasmuch as the center of the bone is usually softer than its edges, the connecting web portion 11 finds little purchase for preventing relative rotation of the two fragments B1 and B2. However, the flanges 12 and 13 are imbedded in harder bone and they provide suitable anchorage in the two fragments of the bone. Inasmuch as the flanges 12 and 13 project in opposite directions, they tend to oppose relative rotation of the fragments in

either direction when torque is exerted on the fragments.

Figure 5 also illustrates the use of the nail 10 as a bone plate for anchoring it more firmly to the shaft of the femur F. Thus, the projecting portion of the nail 10 may be bent down along the shaft of the femur and secured thereto by means of suitable screws 16 and 17 in the usual way. Inasmuch as the flanges 12 and 13 project only a very short distance beyond the center web 14, the inner flanges will fit closely against the bone, allowing the web 11 to come substantially into contact with the bone. At the same time, the oppositely directed portions of the flanges do not extend outwardly far enough to cause irritation of the tissues overlying the portion of the nail affixed to the bone.

It will be understood, of course, that the nail or a part thereof can be used solely as a bone plate and that sections of any desired length may be cut from the nail 10 to form such bone plates.

Preferably, the nail 10 is provided with a pointed and sharpened edge 18 to facilitate its insertion into the bone. However, this end may be cut off if the nail is to be used as a bone plate.

The device may be modified to facilitate its insertion into the bone. Such a modification is disclosed in Figures 3 and 4 of the drawings. In this form of the nail, the center web of the nail 20 is provided with the apertures 21 corresponding to the apertures 14 of the nail 10 described above. However, the nail 20 differs in that the webs 22, 23, etc. between the apertures 21 are punched out in opposite directions to form guides for receiving a pin 24 which extends and can be slid lengthwise of the device 20. In use, the pin 24 is driven into the bone to form a guide for receiving the nail 20. The nail 20 is then slipped over the projecting end of the pin 24 and is driven along the pin 24 so that the nail is guided accurately into position in the bone fragments. In this way, it is only necessary to observe the depth to which the nail is driven to assure its proper positioning in the bone.

It will be understood from the preceding remarks that a nail has been provided which is capable of use not only as a bone nail or pin but which is equally suitable for use as a bone plate, and, therefore, it is capable of replacing a great variety of different types of nails and bone plates which were heretofore regarded as necessary to meet the requirements of different types of fracture fixation operations. In so far as the present invention is concerned, these requirements may be satisfied by providing a plurality of different sizes of the devices only without modifying their shape substantially. Thus, when the devices embodying the present invention are made in a series of three or four widths each varying by about an eighth of an inch, practically all types of fractures can be fixed by the selection of a device of suitable width for the purpose. In this way, instead of requiring nearly five hundred different types of bone plates and nails, it is possible with the present invention to attain the same results with only about three or four different sizes of the device.

It will be understood that the nails embodying the present invention are susceptible to modification in the type of material from which they are made and in their shape and dimensions and in the size and shape of the openings therein. Therefore, the forms of the invention described herein should be considered as illustrative of the

invention and not as limiting the scope of the following claims.

I claim:

1. A fracture nail comprising an elongated strip of metal having narrow flanges projecting in opposite directions from both of its edges, and a chisel-like edge at one of its ends. 5

2. A fracture nail comprising an elongated strip of corrosion-resistant metal having a row of perforations extending lengthwise of said strip, and narrow web portions between said perforations bent alternately in opposite directions from said strip to form a channel for receiving a guide pin. 10

3. A fracture nail comprising an elongated strip of corrosion-resistant metal having a row of perforations extending lengthwise of said strip, narrow web portions between said perforations bent alternately in opposite directions from said pin. 15

strip to form a channel for receiving a guide pin, and narrow flanges projecting in opposite directions from each longitudinal edge of said strip.

EDWARD J. HABOUSH.
